METHOD OF SIDETRACKING WELLS

Arthur L. Armentrout and Elwin B. Hall, Los Angeles, Calif., assignors, by direct and mesne assignments, to Security Engineering Co. Inc., a corporation of California

Application February 16, 1938, Serial No. 190,739

11 Claims. (Cl. 255—1)

This invention relates to well drilling and producing operations and relates more particularly to a method and apparatus useful in producing and sidetracking deep wells such as oil wells and gas wells.

When an oil well or gas well has been drilled and put in condition for production, it is sometimes found that the well does not produce in paying quantities or that it produces too large a proportion of water or other unwanted fluid. In other instances a well will become exhausted of its oil or gas after a short period of production. In such cases, and under various other circumstances, it is sometimes desirable to divert or sidetrack a well or deepen the well after it has been finished and equipped for production. Heretofore when such a course was to be pursued it was necessary to pull the liner from the well or to attempt to cut through the wall of the set steel liner or the set steel casing. Much difficulty and delay is often encountered in the removal of a liner, particularly if the well has been producing for some time, and it is usually quite difficult to sidetrack through a set steel casing or liner.

An object of this invention is to provide a rapid and easily performed method for diverting or sidetracking a well that is equipped with a set casing or liner for production purposes, and that may or may not have been in production.

Another object of this invention is to provide a simple method for sidetracking or diverting a well at a predetermined point or elevation through the set casing or liner and in any selected direction.

Another object of the invention is to provide a method for sidetracking a well that does not necessitate cutting through the set water string or casing, nor the breaking of the cement seal about the same whereby a liner of the same size as originally employed may be installed in the diverted well and avoiding the necessity of landing and cementing a smaller casing.

Another object of this invention is to provide a method for sidetracking a completed well in any selected direction that does not necessitate the employment of special milling tools, or the like, for cutting out through the casing or liner.

Another object of the invention is to provide a method for sidetracking a well that assures the complete sealing off of the strata bearing unwanted fluid and penetrated by the lower portion of the well, as originally drilled.

Another object of this invention is to provide an apparatus for equipping a well for the produc-

tion of its fluid that facilitates the easy sidetracking of the well.

Another object of the invention is to provide apparatus for equipping a well for production that provides for the subsequent sidetracking of the well at a predetermined point if and when such sidetracking becomes necessary or desirable.

Another object of the invention is to provide a casing for lining a well that has a portion or section formed of drillable material whereby the well may be easily sidetracked from said section if and when it becomes desirable to sidetrack the well.

A further object of the invention is to provide a liner for a producing well that embodies a portion or section formed of drillable material whereby the well may be easily and quickly diverted or sidetracked from said section without removing the liner from the well and without employing milling tools or the like to cut through a steel casing or liner.

Other objects and features of our invention will be better and more fully understood from the following detailed description of typical forms and applications of the apparatus and typical manners of carrying out the method, throughout which description reference may be had to the accompanying drawings, in which:

Fig. 1 is a longitudinal sectional view of the lower portion of a typical well showing one form of apparatus or liner arranged therein for production purposes. Fig. 2 is an enlarged fragmentary longitudinal sectional view of the well and liner illustrated in Fig. 1 showing the lower portion of the well occupied by cement. Fig. 3 is a view similar to Fig. 2 showing the upper portion of the liner and body of cement drilled out and a whipstock set in place to divert a drilling tool. Fig. 4 is a view similar to Fig. 1 illustrating another form of liner or casing arranged in the well. Fig. 5 is an enlarged fragmentary longitudinal sectional view illustrating the lower part of the casing of Fig. 4 cemented in the well and a portion of the casing drilled away, and Fig. 6 is a view similar to Fig. 5 showing a whipstock in position to divert a drilling tool.

The method of the present invention may be carried out with the employment of apparatus constructed to suit different conditions that may be encountered in deep wells such as oil wells and gas wells. In the drawings we have illustrated two typical forms of apparatus of the invention employed in the performance of the method. It is to be understood that the invention

is not to be construed as restricted to the use of the typical preferred apparatus illustrated, or to the employment of the method under the particular circumstances about to be described. It is believed that the method will be better understood following a description of the typical preferred apparatus illustrated in the drawings and we will first proceed with a description of the apparatus.

In Figs. 1, 2 and 3 of the drawings we have illustrated the lower portion of a typical well W. The well W extends down through a number of spaced active or producing strata. In the simple case illustrated the well W penetrates a lower producing stratum A, a non-producing stratum B overlying the stratum A, a productive stratum C overlying the stratum B, and a non-producing stratum D overlying the stratum C. A casing 10 extends down in the well W from the ground surface and has its lower portion embedded or set in a body of cement 11 in the portion of the well penetrating the non-producing stratum D. The open lower portion of the well W, continuing beyond the casing 10, may vary to a great extent in length, for example, it may be only one hundred feet in length or it may be several thousand feet in length.

The form of apparatus of the invention illustrated in Figs. 1, 2 and 3 of the drawings is in the nature of a casing or liner L for the open lower portion of the well W and the liner L comprises, generally, an elongate tubular body having a drillable portion or section 12 and having one or more perforated portions as will be herein after described.

The liner L is adapted to be set or arranged in the well W to extend through its open lower portion. The liner L is provided to admit the fluids produced by the producing sands or strata A and C and to conduct the same upwardly to the casing 10. The liner L serves to screen out or prevent the entrance of sand or other solid matter and to prevent caving or collapsing of the open lower portion of the well W. In most applications or installations the body or liner L is made up of a number of pieces or sections connected to form an elongate tubular structure. In the typical case illustrated the liner L comprises a perforate section 13 in the portion of the well W penetrating the producing stratum A, an imperforate section 14 in the part of the well penetrating the stratum B and the above mentioned drillable section 12 extending through the part of the well penetrating the stratum C.

Where the drillable section 12 extends through the part of the well W penetrating the producing stratum C, it is perforate to admit fluid of the said stratum. While we have shown the perforate section 13 as being the lowermost section of the liner L it is to be understood that the liner may extend downwardly beyond the section 13 and may include other lower sections. The perforate sections 12 and 13 preferably extend completely through, or through substantial portions of their respective strata C and A. The perforate sections 12 and 13 may be provided with screen openings of various natures for the admission of the produced fluids. In the particular structure illustrated the sections 12 and 13 are provided with multiplicities of circumferentially and longitudinally spaced slots 16 for admitting fluid from the well W to the interior of the liner L. The imperforate section 14 extends between and connects the two perforate sections 12 and 13 and in practice may be of any length

that provides for the correct spacing of the sections 12 and 13 so that they are located in the producing strata C and A. Accordingly, the imperforate section 14 may be made up of any required number of connected lengths of tubular pieces or members.

In the drawings we have shown the sections 13 and 14 connected by a threaded collar or coupling 17 and the sections 12 and 14 connected by a similar collar or coupling 18. The liner L may be set, hung or retained in the well W in any selected manner. In the typical installation illustrated the liner L is supported on the lower wall of the well W, the lower section 13 being provided with a shoe 19 for engaging the bottom of the well. In accordance with the invention the sections 13 and 14, the couplings 17 and 18, and the shoe 19 may be formed of steel in the usual manner.

The drillable section 12 is a feature of the invention. The section 12 is such that it may be easily and quickly drilled away or drilled up when it becomes necessary or desirable to sidetrack the well. The removable or drillable section 12 is formed of a material that may be easily broken up or drilled up by a suitable drilling tool operated in the well. It is preferred to form the section 12 of aluminum or an aluminum alloy which can be readily drilled up by a suitable tool when in the well. The invention contemplates the formation of the section 12 of other drillable materials such as cement, glass, "Bakelite", hard rubber composition, and the like, that possess the desired qualities. A desirable characteristic of the aluminum or aluminum alloy of which the section 12 may be formed is its low specific gravity whereby the fragments or cuttings of the section 12 formed when the section is drilled away readily flush or wash from the well W with the circulation fluid discharged from the drilling tool.

It is preferred that the liner L extend upwardly into the lower portion of the set well casing 10. In most installations it is preferred to locate the drillable section 12 in the liner L so that it occurs at or adjacent the lower end of the set casing 10. It is preferred to provide a head or outwardly projecting flange 20 on the upper end of the section 12. It will be observed that the several sections or parts of the liner L, with the exception of the section 12, may be formed of steel in the usual manner.

In carrying out the method of the invention with the apparatus illustrated in Figs. 1, 2 and 3, it will be assumed that the well W has been completed as illustrated and described above. Upon completion of the well the liner L is made up or assembled. The liner L is constructed so that its perforate section 13 will extend through the stratum A, its imperforate section 14 will extend through the stratum B and its perforate drillable section 12 will extend through the stratum C and project into the casing 10. The liner L may be run into the well W in the usual manner to the selected position. As described above, the liner L may be allowed to rest on the bottom wall of the well W when in its final position.

Following the setting or positioning of the liner L the well W is allowed to produce from the strata A and C and the other producing strata, if any. In some instances it may be desirable or necessary to pump the well in the manner well known to those skilled in the art. It may be assumed that the well W is allowed to produce until its oil sands or producing strata become exhausted

of the wanted fluid, produce in insufficient quantities, or flood the well with water, or it may be assumed that upon completion of the well or immediately thereafter the well fails to produce in paying quantities. Under such circumstances it may be desired to divert or sidetrack the well W in an attempt to penetrate an oil bearing sand out of alignment with the well, or to reach a lower oil sand. The method of the invention materially facilitates such a sidetracking operation.

In carrying out the sidetracking operation a body of cement slurry S is introduced to the well W. The cement S may occupy the well W from its lower end to a plane at or above the lower end of the set casing 10, as shown in Fig. 2. This, of course, imbeds or encases the liner L in a body or plug of cement slurry S. It is to be understood that it is not essential to encase the entire liner L in the cement S. The plastic cement or cement slurry S may be delivered to the lower portion of the well in any of the well known manners. Following the introduction of the cement slurry S, it is permitted to set and harden.

Subsequent to the hardening of the cement slurry S, a suitable well drilling tool such as a rotary drilling bit of the drag type, or a rotary rock bit, is run into the well W and is operated to drill out the upper portion of the body of cement S and the encased drillable liner section 12. The section 12 being completely encased in the cement S and being formed of a drillable material is readily drilled up into small fragments or cuttings by a suitable well drilling tool. The cuttings of the section 12 and the cuttings of the cement S are flushed from the well W with the circulation fluid discharged under pressure from the drilling tool. The drilling operation is started at or above the upper end of the drillable section 12 and continues to a selected point some distance below the lower end of the set casing 10. In practice the drilling operation may continue until the drilling tool engages the coupling 18 at which time the exposed major portion of the section 12 has been completely drilled away. The engagement of the drilling tool with the steel coupling 18 is accompanied by marked resistance to the cutting action of the drilling tool and this indicates to the operator that the section 12 has been completely drilled away.

Fig. 3 of the drawings illustrates the condition of the well W following the drilling away of the section 12 and the upper portion of the body of cement S. The drilling away of the section 12 and the upper portion of the body of cement S provides or leaves an upwardly facing shoulder or surface 21 at the upper end of the collar or coupling 18. Where the drillable section 12 is of substantial length, the drilling operation just described provides or leaves a portion of the well W of substantial length that is clear and open. It will be observed that the cementing in of the liner L preceding the drilling operation completely seals off the stratum A and any other producing strata below the coupling 18 to prevent unwanted fluid in such strata from entering the well W.

Following the drilling up of the section 12 and the drilling away of the upper portion of the body of cement S, a whipstock 22 is run into the well W to occupy a position in the open portion of the well. The whipstock 22 may be arranged on the surface 21 to be supported thereby and to occupy a desired or selected position in the open portion of the well W at the stratum C or

D. In accordance with the invention any suitable type of whipstock may be utilized. The whipstock 22 illustrated has an inclined surface 23 for diverting the drilling tools and has a ring or sleeve 24 at its upper end adapted to fit about the drill stem or operating string 25 of a sidetracking bit 26. The particular whipstock 22 illustrated may be run into the well W on the string 25 with its sleeve 24 releasably connected with the bit 26. This facilitates the orienting of the whipstock 22 by means of the drilling string 25. The above described drilling away of the section 12 and the upper portion of the body of cement S leaves a part of the well W free and unobstructed so that the whipstock 22 may be easily oriented and set as desired.

When the whipstock 22 has been arranged in the selected position the drilling string 25 is rotated and fed downwardly so that the engagement of the bit 26 with the surface 23 results in sidetracking of the bit. As illustrated in Fig. 3 of the drawings the bit 26 drills into the side wall of the well W to form a hole or bore 28 that is inclined with respect to the well W. When the bit 26 leaves the whipstock 22 it may continue in the path indicated. It is to be particularly noted that the sidetracking bit 26 acts directly upon the earth formation at the side wall of the well W and does not engage or penetrate any part of the casing 10 or the liner L. This clearly facilitates the sidetracking operation and assures a successful sidetracking of the well W. When the bit 26 has made a bore 28 of the desired length the string 25 may be withdrawn from the well to remove the bit and the whipstock 22. It will be obvious how the well bore or sidetrack bore 28 may be continued or deepened with suitable drilling tools to the desired depth.

Figs. 4, 5 and 6 illustrate another form of apparatus of the invention arranged in a well W' having an open lower portion penetrating an oil sand or productive stratum A', an unproductive stratum B', a productive stratum C' and a non-productive stratum D'. A casing 10a is set in the well W' and has its lower portion cemented in the stratum D'. The apparatus of the invention shown in Figs. 4, 5 and 6 is in the nature of a casing 30 having an upper portion 31 extending down through the casing 10a, a drillable section 32 in the open portion of the well W' and perforate sections 33 and 34.

The casing 30 is provided to line or case the open lower portion of the well W' and to conduct the produced fluid to the ground surface. The casing 30 is an elongate tubular structure or assembly extending through the well W' and to or through the lower producing stratum A'. The upper portion 31 of the casing 30 may be made up of a large number of lengths of casing and is of sufficient length to extend from the upper end of the well to a point adjacent or below the lower end of the casing 10a. The major upper portion 31 of the casing C may be constructed of steel in the usual manner. The lower end part of the portion 31 preferably extends into the open portion of the well W' and is preferably provided with a cement basket 35. Cement 36 is introduced into the well W' above the basket 35 to cement or set the casing 30 in the well. In actual practice the portion 31 may extend a considerable distance beyond the lower end of the casing 10a and the cement 36 may encase or surround the portion 31 for a substantial distance.

The drillable casing section 32 is preferably,

though not necessarily connected with the lower end of the portion 31. A suitable threaded collar or coupling 37 may connect the upper end of the section 32 with the lower end of the portion 31.

- 5 5 In the case illustrated where the section 32 extends through the non-productive stratum D', the section 32 is imperforate. In accordance with the invention the section 32 is drillable, that is, it is formed of a material that may be drilled up or reduced to small fragments or cuttings by a suitable well drilling tool when the casing 30 is in the well W'. It is preferred to construct the section 32 of aluminum or a suitable aluminum alloy which can be readily drilled up. It is to be understood 10 that the section 32 may be formed of other drillable materials such as glass, cement, "Bakelite", hard rubber composition, etc. In the drawings we have shown the lower end of the drillable section 32 connected with the perforate section 33 by a collar or coupling 38. It is to be understood, however, that one or more imperforate sections or lengths of casing may be interposed between the lower end of the drillable section 32 and the perforate section 33. The couplings 37 and 38 are preferably formed of steel 15 or the like.

The perforate casing sections 33 and 34 are lengths or assemblies of tubular casing stock perforated or provided with spaced slots 39. An imperforate casing section 40 is interposed between the perforate sections 33 and 34 to extend through the non-productive stratum B'. Suitable couplings 41 may connect the perforate sections 33 and 34 with the imperforate section 40. A shoe 42 may be provided on the lower end of the lower perforate section 34. The sections 33, 34 and 40, the couplings 38 and 41 and the shoe 42 may be formed of steel. The casing 30 may be suspended from the top of the well by a casing head or the like (not shown), so that the shoe 42 hangs free of the bottom of the well W'. It will be observed that the casing 30 with the exception of its section 32 may be formed of steel in the usual manner.

- 45 45 In carrying out the method of the invention with the apparatus illustrated in Figs. 4, 5, and 6, it will be assumed that the well W' has been drilled to the depth shown in Fig. 4 and that the casing 10a has been set or cemented in place. The casing 30 is made up and run into the well in the usual manner. The casing 30 is assembled so that its several parts and sections will be in the positions illustrated in Fig. 4 of the drawings when the casing is set or hung in the well. Following 50 the running of the casing 30 to the proper position in the well, the cement 36 is introduced into the well W' to encase the section 31 for some distance above the basket 35. This cement 36 may be introduced in any of the well known manners 55 and when set and hardened serves to hold or cement the casing in the well and to seal off the producing open lower portion of the well W' from the remainder of the well.

When the casing 30 has been set as described 60 above, the well may be allowed to produce from its strata A' and C' and if necessary, may be pumped. The produced or pumped fluid enters through the perforations or slots 39 in the sections 33 and 34 and passes up through the casing 30. 65 After a prolonged period of production, the well may become depleted of its oil and gas or may become sanded up. For the foregoing or other reasons, it may be desired to redrill or deepen the well by diverting it from the original hole. In 70 accordance with the invention, the first step in

75 pursuing this course is to introduce a body of cement 44 into the well W' to encase or cement in the casing sections 32, 33, 34 and 40. The cement 44 may be introduced through the casing 30 in a plastic state or in the form of a slurry and forced out through the slots 39 to occupy the annular space in the well W' surrounding the casing. The cement 44 may also occupy the interior of the casing 30 to a point adjacent or below the lower end of its portion 31. It is preferred to introduce sufficient cement 44 to substantially completely encase and occupy the drillable section 32 as well as the lower portions of the casing 30. The cement 44 is allowed to set and harden to rigidly secure the lower parts of the casing 30 in the well W'. 10

Following the hardening of the cement 44 the section 32 or a part of the section 32 is drilled out. In performing this operation a suitable well bit, underreaming tool, wall scraper or the like, 20 is run down through the casing 30 on an operating string and is operated to drill up the section 32. This drilling up of the section 32 is accompanied by the drilling away of the cement 44 occupying the interior of the section 32 and a portion or all of the cement enclosing or surrounding the section 32. As the section 32 is set or imbedded in the cement 44, it is readily drilled up or reduced to small cuttings or fragments by the drilling tool or reaming tool. The circulation 30 fluid discharging under pressure from the drilling or underreaming tool flushes away the cuttings or fragments of the section 32 and the cuttings of the cement 44 and carries the same to the ground surface. 25

In practice it may be preferred to drill away a substantial portion of the section 32. Fig. 5 of the drawings illustrates the condition of the equipment following the drilling or underreaming operation just described. As illustrated in 40 Fig. 5 of the drawings, a substantial part of the section 32 has been cut away to leave an enlarged opening 45 in the body of cement 44. The opening 45 may be of such diameter that a thin wall of cement 44 remains to surround it. It is 45 to be understood, however, that the tool employed to drill up the section 32 may be capable of drilling away all of the cement 44 around the section 32 to expose the earth formation at the side wall of the well W'. When a sufficient part of the section 32 has been drilled up the drilling tool is withdrawn from the well W'. 50

The next phase or step of the method is the arrangement of a suitable whipstock 46 in the opening 45. The whipstock 46 may be of any 55 suitable type and may be set and oriented in any known manner. The whipstock 46 illustrated in the drawings is of the same type as the whipstock 22 and is adapted to be run into the well through the casing 30 on a sidetracking bit 26a. 60 The sidetracking bit 26a is secured to the lower end of an operating string 47 and the whipstock 46 has a collar or sleeve 48 that is releasably connected with the bit when the same is run through the casing. This association of the whipstock 46 with the bit 26a and the string 47 facilitates the orienting of the whipstock by means of the string. The whipstock 46 is adapted to be arranged in the opening 45 so that its lower end engages the bottom wall 49 of the said opening. 70 This bottom wall 49 is provided by the body of cement 44 and constitutes a firm dependable footing for the whipstock.

When the whipstock 46 has been oriented and set in the opening 45, the string 47 is manipu- 75

lated and operated so that the bit 26^a is deflected by the surface 50 of the whipstock to drill a diverging bore 51 in the earth formation. The whipstock 46 may rest against the side wall of the opening 45 and the bottom wall 49 of the opening and is dependably supported for the whipstocking operation. It is to be particularly noted that the bit 26^a diverted by the whipstock 46 may readily drill out through the thin wall of cement 44 and then pass directly into the earth formation without contacting a steel casing or a steel liner. The bit 26^a, of course, may be operated to drill to any desired depth and the bore 51 may be continued and directed as desired.

Having described only typical preferred forms and applications of the method and apparatus of our invention, we do not wish to be limited or restricted to the specific details herein set forth, but wish to reserve to ourselves any modifications or variations that may appear to those skilled in the art or fall within the scope of the following claims.

Having described our invention, we claim:

1. The method of operating a well which comprises arranging in the well a tubular body having at least one perforate portion for receiving the fluid from the earth formation and having a drillable portion, allowing said fluid to enter through said body, and subsequently when occasion requires sidetracking through said drillable portion.

2. The method of operating a well which comprises providing a tubular body having a drillable portion and having at least one perforate portion for admitting fluid, arranging the body in the well so that the fluid from the earth formation may enter through said perforate portion, drilling up said drillable portion to leave a portion of the well clear, and then sidetracking the well from said clear portion.

3. The herein described method which comprises providing a tubular body having at least one perforate portion and a portion formed of drillable material, arranging the body in the open productive portion of a well so that the perforate portion may receive the formation fluid, and subsequently when occasion requires operating a tool in the well to drill up said drillable portion of the body to leave a part of the well clear and then sidetracking the well through said clear part.

4. The herein described method which comprises providing a tubular body having at least one perforate portion and a portion formed of drillable material, cementing the body in the open productive portion of a well so that the perforate portion may receive the formation fluid, subsequently when occasion requires drilling up said drillable portion, and then sidetracking the well from the area of drilling up said drillable portion of the body.

5. The herein described method which comprises providing a tubular body having at least one perforate portion and a portion formed of drillable material, arranging the body in the open productive portion of a well so that the perforate portion may receive the formation fluid, cementing the said body in the well, subsequently when occasion requires operating a tool in the well to leave a part of the well clear, and then sidetracking the well by arranging a whipstock in said clear

part of the well, and directing a drilling bit from the well by means of the whipstock.

6. The herein described method which comprises providing a tubular body having at least one perforate portion and a portion formed of drillable material, arranging the body in the open productive portion of a well so that the perforate portion may receive the formation fluid, subsequently when occasion requires operating a tool in the well to drill up said drillable portion of the body to leave a part of the well clear, arranging a whipstock in said clear part of the well, and then deflecting the well by operating a drilling tool against the whipstock to divert the drilling tool into the formation from said clear part of the well.

7. The herein described method useful in the operation of a well having an open producing lower portion which comprises providing a liner having a perforate portion and a drillable portion, arranging the liner in the open portion of the well to permit production of the well fluids through the liner, subsequently when occasion requires cementing the liner in the well, operating a tool in the well to drill up said drillable portion and part of the cement to provide an open space in the well, arranging a whipstock in said open space, and diverting a drilling tool by means of the whipstock to divert the well.

8. The herein described method useful in the production of a well having an open producing lower portion which comprises arranging a casing in the well having a drillable portion and a perforate portion in said producing portion of the well, producing the well fluids through the casing, subsequently when occasion requires operating a tool in the well to drill up said drillable portion and thus leave an open space in the well, arranging a whipstock in the said open space, and then directing the drilling tool by means of the whipstock to divert the well.

9. The herein described method useful in the production of a well having an open producing lower portion which comprises arranging a casing in the well having a drillable portion and a perforate portion in said producing portion of the well, producing the well fluids through the casing, subsequently when occasion requires cementing up said producing portion of the well, operating a tool in the well to drill up said drillable portion and thus leave an open space in the well, arranging a whipstock in the said open space, and then directing a drilling tool by means of the whipstock to divert the well.

10. The method of operating a well which comprises arranging in the well a tubular body having at least one portion for receiving the fluid from the earth formation and having a drillable portion, allowing said fluid to enter through said tubular body, and subsequently when occasion requires sidetracking the well through said drillable portion.

11. The method of operating a well which includes arranging in a well a tubular body having one or more connected lower steel sections and one or more readily drillable sections thereabove, and subsequently when occasion requires closing at least the top of the lower steel sections and deflecting the well through the locality of the drillable sections.
